UNITED STATES PATENT OFFICE.

HERBERT E. HAWES, OF BROOKLYN, NEW YORK, ASSIGNOR TO COLBY & CO., OF SAME PLACE.

MULTIPLE-BUTTONHOLE-SEWING MACHINE.

SPECIFICATION forming part of Letters Patent No. 595,171, dated December 7, 1897.

Application filed January 11, 1897. Serial No. 618,804. (No model.)

To all whom it may concern:

Be it known that I, HERBERT E. HAWES, a citizen of the United States, residing in Brooklyn, in the county of Kings and State of New York, have invented a new and useful Improvement in Multiple-Buttonhole-Sewing Machines, of which the following is a specification.

This invention relates for the most part to multiple-buttonhole-sewing machines of the kind exemplified in Letters Patent No. 363,678, granted to William Randel May 24, 1887, and No. 441,058, granted to Thomas E. Colby November 18, 1890, in which a plurality of buttonhole-sewing mechanisms are combined and operated in unison for sewing a number of buttonholes simultaneously in a piece of fabric requiring such number of buttonholes—as, for example, buttonhole-waistbands for boys' trousers, cuffs, collars, &c.

The particular objects of my invention are to provide a multiple-buttonhole machine of this class in which the even and simultaneous descent and elevation of the several sewing-needles will be positively insured, as well as the harmonious operation of the thread-take-up devices and shuttles, and to provide for readily adjusting the several needles and buttonhole work-clamps with respect to each other, so as to sew buttonholes at different distances apart. I attain these and other ends by various novel features of construction and combinations of parts, and in order that my invention may be fully ascertained I shall first describe in detail the mode in which I carry the invention into practice and then point out its various features in the claims.

Reference is to be had to the accompanying drawings, forming part of this specification, in which like parts are designated by the same letters in all the figures.

Figure 1 is an end elevation of a multiple-buttonhole machine embodying my invention. Fig. 2 is an elevation of the opposite end of the same. Fig. 3 is a partial front elevation of the same, partly in section. Fig. 4 is a partial plan view of the same. Fig. 5 is a sectional plan view on the line 5 5, Fig. 3. Fig. 6 is a sectional plan view on the line 6 6, Fig. 8. Fig. 7 is a sectional plan view on the line 7 7, Fig. 8. Fig. 8 is a sectional

view on the line 8 8, Fig. 4. Fig. 9 is a sectional view on the line 9 9, Fig. 3.

A designates the frame of the machine illustrated which I designed for sewing and cutting eight buttonholes abreast of each other in waistbands for boys' trousers at any of the distances apart usually required for the various sizes of waistbands on the market, the spaces between the third and fourth buttonholes being usually made greater than those between the remaining buttonholes.

I prefer to construct the frame A with end standards B B', between which I arrange the (in this example of my invention) eight buttonhole stitching and cutting mechanisms, and which standards I rigidly connect by horizontal bed members C and longitudinal bars D.

In bearings E² at the upper ends of the end standards B B', I prefer to mount a longitudinal driving-shaft E, carrying a driving-pulley E', and on said driving-shaft I fix at appropriate distances apart a number of thread-take-up cams F, corresponding to the number of (in this instance eight) buttonholes to be stitched at one time. With the respective take-up cams F, I engage thread-take-up levers F', which I pivot to the upper longitudinal bar D of the frame A, so that eight threads will be evenly and simultaneously taken up for the eight buttonhole-sewing mechanisms.

G designates the sewing-needles, which in this instance are eight in number.

In order that the needles G may be evenly and simultaneously depressed and elevated in harmony with the operation of the thread-take-up devices above described and may be adjusted to work the buttonholes with various spacings, I mount said needles in a horizontal line in holders H, having each, by preference, an L-slot H' to fit and slide lengthwise on an L-rail H², formed on a multiple needle-carrier I. The needle-carrier I extends transversely across the entire machine and is arranged to be reciprocated vertically in guides I', fixed on the end standards B B' of the frame. Thus the various needle-holders H may be adjusted with the needles any required distances apart on the carrier-rail H², and may be secured in such adjustment by set-screws H³, which I

provide in said needle-holders, while the several needles will be reciprocated with the carrier I in exact unison.

To actuate the reciprocating needle-carrier I by the driving-shaft E, I prefer to connect both ends of the needle-carrier outside the end standards B B' pivotally with rods J, the upper ends of which are strapped to eccentrics J', fixed on the driving-shaft E, so that the several needles G will be accurately depressed and elevated in a horizontal line with each revolution of the driving-shaft.

Beneath each needle G, I erect on the bed members C a longitudinal box K, in which I prefer to mount in bearings K' a shuttle-shaft K², carrying in this instance an oscillating shuttle K³ of ordinary description to coöperate with its respective needle G in forming the stitches, the top of each box K forming the work-plate K⁴ for the respective stitch-forming mechanism.

To actuate the several shuttles K³ in perfect unison with the needles G, I prefer to form each shuttle-shaft K² with a crank K⁵, which I engage in a well-known manner with the slotted end K⁶ of a rocking lever K⁷. I actuate the several rocking levers K⁷ simultaneously by connecting them pivotally with links K⁸, the upper ends of all of which are connected pivotally with a vertically-reciprocating horizontal cross-head L, which I mount to work vertically in guides L', fixed on the end standards B B'.

In order that the shuttles K³ and work-plates K⁴ may be adjusted transversely to correspond with the adjustment of the needles before described, I mount the several shuttle-boxes K to slide transversely with the shuttle-shaft bearings on guide-rails A', fixed on the frame A, and I connect the several shuttle-actuating links K⁹ to headed pivot-studs K¹⁰, which are mounted adjustably in a T-slot K¹¹, running lengthwise of the cross-head L, and may be fixed in the desired adjustment by washers K¹² and binding-nuts K¹³, so that the shuttle-actuating links K⁹ may be adjusted to correspond with the adjustment of the shuttle-shafts K² and boxes K.

I effect the operation of the vertically-reciprocating shuttle-actuating cross-head L and oscillating shuttles K³ in unison with the needles G by pivotally connecting both ends of the cross-head L outside the standards B B' with bearing-boxes L², playing in guides L³ on the rear ends of beam-levers L⁴, which are mounted medially on pivots L⁵ on the end standards B B' and the front ends of which have guides L⁶, in which play boxes L⁷, connected by pivots with the vertically-reciprocating needle-carrier I, so that the several shuttles will be oscillated in exact and proper unison with the reciprocation of the needle-carrier I and needles G.

M designate the several work-clamps, of which I naturally in this illustration of my invention provide eight and which are all

actuated simultaneously and in unison by means of a multiple work-clamp carrier having a buttonhole feed motion generally, as in the aforesaid prior patents to Wm. Randel, 70

No. 363,678, and Thomas E. Colby, No. 441,058; but I prefer to attach the work-clamps M adjustably to the transverse bar M' of the work-clamp carrier by dovetailing the bar M' and fitting it to corresponding slots in the work-clamps M, the outer walls of said slots being formed by separate clamping-plates M², which are secured in place by screws M³, so that the work-clamps can be readily adjusted transversely, but along the carrier-bar M', to correspond with the described adjustments of the needles and shuttles, and can be as readily fixed in such adjustment. I also prefer to form the arms M⁴ of the presser-feet of the work-clamps M with segmental bearings M⁵, 85

which I pivot on and mount to slide along the head of a rail M⁶, extending along and fixed on the carrier-bar M', so that when the work-clamps M are adjusted along the bar M', as before described, the presser-feet will likewise be adjusted along the rail M⁶. I further prefer to provide springs M⁷, tending to raise the presser-feet and to effect the even and simultaneous depression of the presser-feet by means of a cam-bar M⁸, extending along 95 and pivoted to the carrier-bar M' and adapted to coöperate with a cam extension M⁹ of each presser-foot arm, said cam-bar being provided, as illustrated in the aforesaid patent to T. E. Colby, No. 441,058, with an operating-arm M¹⁰ 100 and treadle, (not shown,) which I employ for clamping all the presser-feet simultaneously, and also with a spring M¹¹ for returning the cam-bar, and thus allowing the presser-feet to be unclamped by their respective springs M⁷. 105

To impart an even and simultaneous buttonhole feed motion to the several work-clamps M, I secure the carrier-bar M' at its ends to upright but depending arms N, fixed to a horizontal guide-plate N', which, together 110 with the bar M', constitutes a work-clamp carrier substantially like that described in the aforesaid patent to T. E. Colby, No. 441,058. The guide-plate N' is provided with longitudinal dovetail guides, in which works 115 a second horizontal guide-plate N², having transverse guides, in which works a third guide-plate N³, mounted to work on fixed guides N⁵, extending transversely along the frame A, substantially as described in said 120 patent to T. E. Colby, although in said patent the word "transversely" is used to mean lengthwise of the buttonholes to be stitched, while in this specification it means transversely of the buttonholes, and, conversely, 125 the word "longitudinally." As described in said patent to T. E. Colby, I impart to the guide-plate N' a reciprocating feeding motion lengthwise of the buttonholes, to the guide-plate N² a reciprocating motion transversely to the buttonholes at the ends of the buttonholes, and to the guide-plate N³ a 130

transversely-vibratory motion to make the individual stitches at the sides of the buttonholes.

To give the longitudinally-reciprocating motion to the guide-plate N' , I prefer to fix on the driving-shaft E a cam-wheel O , having a cam O^{10} , with which I engage a two-armed cam-following lever O' , pivoted to the frame and connected by a rod O^2 with an elbow-lever O^3 , which is pivoted to the frame and is connected by a rod O^4 with a pawl O^5 , which thus intermittently engages and rotates a ratchet-wheel O^6 , mounted to rotate on the upper guide-plate N^3 . The ratchet-wheel O^6 , substantially as shown and described in said patent to T. E. Colby, through a short shaft O^7 , heart-cam O^8 , and cam-followers O^9 , attached to the guide-plate N' , gives the desired longitudinal reciprocatory feeding motion to the guide-plate N' , and hence to the several work-clamps in harmony with the operation of the driving-shaft and the needles.

To give the transversely-reciprocating motion to the work-clamp carrier at the ends of the buttonholes, I prefer to mount on the short shaft O^7 , driven by the ratchet-wheel O^6 , as in said patent to T. E. Colby, a cam P , which engages cam-followers P' on a bar P^2 , connected to the guide-plate N^2 , so that said guide-plate N^2 , and with it the guide-plate N' , mounted thereon, will receive the desired reciprocatory motion in harmony with the operation of the needles, and therefore the several work-clamps be simultaneously reciprocated transversely at the ends of the buttonholes to shift the stitching from one side to the other of the buttonholes.

To impart the required transversely-vibratory motion to the several work-clamps to form the individual stitches at the sides of the buttonholes, I prefer to form the cam-wheel O on the driving-shaft E with a cam-groove Q , substantially as described in said patent to T. E. Colby, and engage with said cam Q a two-armed cam-following lever Q' , pivoted to the frame and connected by a rod Q^2 with the upper guide-plate N^3 , so that said guide-plate N^3 , and with it the guide-plates N^2 and N' and the several work-clamps, will be rapidly vibrated transversely in harmony with the operation of the needles and the individual stitches thus formed at the sides of the buttonholes.

I may also provide for automatically stopping the multiple-buttonhole-stitching mechanism thus described on the completion of the buttonholes by means of any approved form of stop-motion—as, for instance, the well-known Wheeler & Wilson stop-motion, which is operated by a tripper on the ratchet-wheel of the buttonhole feed mechanism.

I effect the even and simultaneous cutting of the several buttonholes, when stitched as described in this example of my invention, by hand, as follows: On each of the several work-plates K^4 , I fix ears R , between which I

pivot a cutter-carrying lever R' , holding a detachable buttonhole-cutter R^2 , which is arranged to coöperate with a correspondingly-slotted cutting-anvil R^3 , set in the work-plate and projecting upward through the opening in the lower clamp-plate R^4 to the level of the cloth plane, so as to cut the respective buttonhole evenly and squarely between the parallel lines of buttonhole-stitching and complete the buttonhole. For actuating each cutter with the required force and precision I prefer to use a toggle-lever consisting of a toggle-link R^5 , pivoted to the cutter-lever R' , and a toggle-arm R^6 , pivoted to the toggle-link R^5 and fixed to a rock-shaft R^7 , mounted on bearings on the work-plate K^4 , and I extend said rock-shaft across all the work-plates and provide it with an operating-arm R^9 and treadle, (which is not and need not be illustrated,) so that a single operator can by said treadle cut all the stitched buttonholes simultaneously and with the requisite force and accuracy.

I make no claim in this particular application to the multiple-buttonhole-cutting mechanism herein shown and described, as the features of invention therein are claimed by me in another application for patent, executed by me March 5, 1897, and filed in the Patent Office July 29, 1897, Serial No. 646,318.

I claim as my invention—

1. In a multiple-buttonhole-sewing machine, the combination, with a plurality of shuttles, a plurality of buttonhole work-clamps, and a buttonhole feed mechanism operating the several work-clamps, of a plurality of needles, a vertically-reciprocating needle-carrier carrying the several needles, guides for the needle-carrier, a driving-shaft, actuating connections between the driving-shaft and the needle-carrier, a vertically-reciprocating cross-head, guides therefor, actuating connections between the cross-head and the several shuttles to operate the shuttles simultaneously, and actuating connections between the driving-shaft, the cross-head and the buttonhole feed mechanism.

2. In a multiple-buttonhole-sewing machine, the combination, with a plurality of shuttles and their shafts, a plurality of buttonhole work-clamps and a buttonhole feed mechanism operating the several work-clamps, of a plurality of needles, a vertically-reciprocating needle-carrier carrying the several needles, guides for the needle-carrier, a driving-shaft, actuating connections between the driving-shaft, the needle-carrier and the buttonhole feed mechanism, a vertically-reciprocating cross-head, guides therefor, actuating connections between the cross-head and the shuttle-shafts, and beam-levers connecting the needle-carrier and the cross-head.

3. In a multiple-buttonhole-sewing machine, the combination, with a plurality of stitch-forming mechanisms, and a buttonhole feed mechanism comprising a reciprocating and transversely-vibrating guide-plate, of a

bar carried by said guide-plate, extending across the several stitch-forming mechanisms, a pivot-rail extending along said bar, and a plurality of work-clamps adjustable along said bar, the presser-feet arms of said work-clamps having bearings adjustable along said pivot-rail.

4. In a multiple-buttonhole-sewing machine, the combination, with a plurality of shuttles and their shafts, a reciprocating cross-head, a plurality of needles, and a reciprocating needle-carrier, a plurality of buttonhole work-clamps, a buttonhole feed mech-

anism, and means for operating the several needles, work-clamps, and cross-head in unison, of actuating connections between the cross-head and the shuttle-shafts including a link for each shuttle-shaft and means for adjusting the said links along the cross-head.

In testimony whereof I have hereunto set my hand the 20th day of April, 1896.

HERBERT E. HAWES.

In presence of—
C. H. COLBY,
GEORGE E. ROGERS.
